United States Patent Office

Des. 179,829
Patented Mar. 5, 1957

179,829

SOFA

Forest Wilson, Chicago, Ill., assignor to Stratford Furniture Corporation, Chicago, Ill., a corporation of Delaware

Application February 25, 1954, Serial No. 29,213

Term of patent 7 years

(Cl. D15—11)

FIG. 1

The design is characterized by the wide rectangular cushioned arm rest in association with the wide, raised side element, which side element merges with the seat front as shown.

I claim:

The ornamental design for a soft, as shown and described.
